SOFT ORE MILLING MACHINE

Eugene W. Wheeler, Foster, Oreg.

Application September 2, 1939, Serial No. 293,296

11 Claims. (Cl. 209—42)

This invention relates to milling or separating machines.

An object of this invention is to provide a milling or separating machine which is adapted to recover gold or other precious metals from soft ore or fine ground ore.

Another object or purpose of this invention is the amalgamating process used in connection with the operation of said machine, so that in the operation of said machine gold ore and other precious metals can be amalgamated from coarse unground ore or fine material.

Another object of this invention is to provide a machine of this character which is so constructed that it may be readily set up in places inaccessible to other machines capable of accomplishing the work.

A further object of this invention is to provide a machine of this character including superposed separating and grinding members and means for securing said members on a rockable platform in such a manner that the separating and grinding members may be easily and quickly angularly adjusted relative to each other.

A still further object of this invention is to provide a mill of this character wherein the precious metals are amalgamated with a liquid metal, such as quicksilver, and wherein the quicksilver is subjected to an agitating action so as to prevent the accumulation of scum or corrosion on the surface of the quicksilver.

A further object of this invention is to provide a mill of this character wherein the agitation of the device is effected in a movement transverse to the movement of the ore therethrough.

A further object of this invention is to provide a mill of this character having rifles extending parallel with the movement of the mill wherein pockets are formed at the forward instead of the rear end of each rifle member within which pockets quicksilver or other suitable amalgamating means is adapted to be disposed.

A further object of this invention is to provide a structure of this kind wherein the soft and earthly material and ore and soft materials in the ore is initially subjected to a grinding and separating treatment. The grinding elements being the hard parts of the ore is later removed by means of grizzlies and the remaining fine and dissolved material passed on through the machine in order to remove the coarse and the very fine particles of the precious metal.

A further object and purpose of this invention is to remove the clay, talc and other earthly materials from the hard ore, the hard ore doing the work of a classifier as well as an amalgamator.

To the foregoing objects and to others which may hereinafter appear, the invention consists of the novel construction, combination and ar-

angement of parts as will be more specifically referred to and illustrated in the accompanying drawings, wherein is shown an embodiment of the invention, but it is to be understood that changes, modifications and variations may be resorted to which fall within the scope of the invention as claimed.

In the drawings:

Figure 1 is a detailed top plan of a soft ore milling machine constructed according to an embodiment of this invention.

Figure 2 is a sectional view partly in side elevation taken on the line 2—2 of Figure 1.

Figure 3 is a longitudinal section taken on the line 3—3 of Figure 1.

Figure 4 is a vertical section taken on the line 4—4 of Figure 3.

Figure 5 is a sectional view partly in top plan taken on the line 5—5 of Figure 2.

Figure 6 is an enlarged fragmentary sectional view taken on the line 6—6 of Figure 1.

Figure 7 is an enlarged fragmentary sectional view taken on the line 7—7 of Figure 2, and

Figure 8 is an enlarged fragmentary sectional view taken on the line 8—8 of Figure 3.

Referring to the drawings the numeral 10 designates generally a base member which is substantially rectangular in plan and the numeral 11 designates generally a platform which is disposed above the base 10. The platform 11 on the under side thereof and at each end is provided in the transverse center thereof with a bearing 12. The bearing 12 is secured to the underside of the platform 11 by means of fastening devices 13. The base 10 adjacent each end thereof is provided with upstanding bearings 14 and rock shafts 15 engage through adjacent bearings 12 and 14 so as to rockably support the platform 11 above the base 10 for rocking movement transverse to the length of the platform 11. A plurality of springs 16 are interposed between the opposed longitudinal sides of the platform 11 and the base 10 so as to cushion the rocking movement of the platform 11 on the shafts or pivotal members 15.

An upper combined grinding and separating box or member 17 is disposed above the platform 11 and a lower box or separating member 18 is disposed immediately above the platform 11. An intermediate box or separating member 19 is disposed intermediate the lower box 18 and the upper box 17. The intermediate box 19 is inclined to the horizontal and is secured at its upper or rear end to the forward end of the upper box 17 by means of a shaft 20 extending through hinge members 21 and 22 carried by the intermediate box 19 and the upper box 17 respectively. The lower box 18 at its forward or discharge end is pivotally secured to the adjacent end of the platform 11 by means of a shaft 23 engaging through

hinge members 24 and 25 carried by the platform 11 and the box 18 respectively. The lower or forward end of the intermediate box 19 is pivotally secured to the upper or rear end of the box 18 by means of a shaft 26 extending through hinge members 27 and 28 carried by the intermediate box 19 and the lower box 18 respectively.

The lower box 18 is supported in upwardly inclined position or at an inclination to the horizontal by means of a pair of wedge members 29 provided with a rabbeted or flanged upper edge 30. The wedge member 29 is adapted to be moved longitudinally of the platform 11 and the box 18 so as to thereby vertically rock the box 18 on the shaft 23 and support the box 18 in the desired fixed position relative to the platform 11. An intermediate wedge 31 is interposed between the lower box 18 and the intermediate box 19, there being a wedge 31 on each side of the boxes 18 and 19. The wedge 31 is provided on opposed tapering edges thereof with flanges 32 and 33 which are adapted to engage on the outer sides of the lower box 18 and the intermediate box 19 respectively. The wedge 31 is held in adjusted position lengthwise of the boxes 18 and 19 by means of clamping bars 34 and 35 which are secured to the inner side of a wedge 31 by means of fastening members 36 and 37 respectively. The clamping bar 34 is adapted to extend downwardly over the inner face of a side wall 38 carried by the lower box 18 and may be clamped against the wall 38 by means of a clamping member 39. The clamping bar 35 extends upwardly of the lower edge of the side wall 40 of the intermediate box 19 and is tightly secured to the wall or side 40 by a clamping bolt 41. The lower wedge 29 is provided on an inner side thereof with a pair of clamping bars 42 which are mounted on bolts 43 and the clamping bars 42 are tightened against the side walls 38 by means of bolts or clamping members 44.

The upper box 17 is supported in a selected angular relation to the intermediate box 19 by means of a pair of wedges 45. These wedges 45 are provided with flanges 46 and 47 on the lower and upper edges thereof which are adapted to engage on the outer surfaces of the side walls 48 carried by the upper box 17. The wedges 45 are held in adjusted position relative to the intermediate box 19, by means of clamping bars 49, which are similar to the clamping members 34 and 35 and the upper edge of each wedge 45 is provided with clamping bars 50 similar to the clamping bars 34 and 35 so that the wedge 45 will be held firmly in adjusted position relative to the intermediate box 19 and the upper box 17.

A plurality of transversely disposed bars 51 extend transversely across the upper edges of the upper side walls 48 and vertically disposed bars 52 are secured by means of nuts 53 and 54 to the platform 11. These bars or rods 52 are disposed in outwardly spaced relation to the side walls of the boxes and the upper ends of the rods or bars 52 are provided with threads 55 upon which upper and lower nuts 56 and 57 are threaded. The nuts 56 and 57 engage on opposite sides of a transverse bar 51 and provide a means for tightly holding the boxes 17, 18 and 19 relative to the rockable platform 11. The boxes 17, 18 and 19, together with the platform 11, are rocked or oscillated transversely of the length thereof by means of an operating member 58. The operating member 58 is constructed in a form of power member and may be water power or any other form of power, or electric motor or an internal

combustion engine which is provided with a drive shaft 59. The drive shaft 59 is provided with an eccentric 60 about which a split ring 61 engages. The eccentric 60 is provided with opposite annular flanges 62 which form a guide and between which the ring 61 engages. A link 63 is secured to the ring 61 and extends downwardly, being connected to a coupling means 64 in the form of a substantially universal coupling having one part 65 mounted on a shaft or pin 66 and the other part 65 is rockably mounted on a shaft 67 disposed at right angles, to the shaft or pin 66. The shaft 67 engages through a bracket member 68 carried by an arm 69 which is secured by fastening members 70 to the platform 11. 15

The upper box 17 comprises a pair of parallel vertically disposed side walls 48, a rear wall 71, and a plurality of inclined bottom walls 72 which are disposed between the side walls 48. The forward ends of the bottom walls 72 are secured to vertical walls 73 extending between the side walls 48 and each bottom wall 72 forms with the adjacent side walls 48 a grinding or separation chamber 74. The bottom walls 72 each have an inner metallic bottom wall 75 which may be formed of iron or the like and the upper surface of the inner bottom 75 is formed with a plurality of longitudinally extending riffles 76. There may be as many grinding and separation chambers 74 in the box 17 as may be desired or considered necessary and 30 at the forward end of each chamber 74 there is provided a vertically and angularly disposed baffle 77. The baffles 77 are hingedly secured to the upper ends of plates 78, which are fastened by fastening devices 79 to the forward ends of the bottom members 72. Each baffle 77 is provided with a slotted arcuate arm 80 through which a holding member 81 engages so that the height and inclination of each baffle member 77 may be angularly adjusted relative to the bottom 72 40 and the inner bottom or riffle member comprising the bottom plate 75 and the riffles 76 by adjusting the arms 80. Each baffle member 77 is provided with an opening 77a therethrough providing water passage and forming means whereby 45 a suction will be developed at the forward end of each grinding and separation chamber 74. The bottom wall 72 of each chamber 74 is inclined forwardly and inwardly thereby forming a pocket 81 within which quicksilver 82 is adapted to be 50 positioned. The quicksilver 82 is positioned at the lower rear end of each chamber 74 so that the precious metal in the form of gold or the like passing over or under the baffle 77 will drop vertically downwardly onto the quicksilver 82 and 55 become amalgamated therewith.

The forward grinding and separation chamber 74a is provided at its forward end with an upstanding wall or baffle 83 and a grizzley or grating 84 is secured to the baffle or forward wall 83 and 60 to a lower wall 85 extending between the side walls 48. The grizzley 84 is adapted to remove the larger particles used in the grinding operation which larger particles may comprise hard rock or the like and the material removed from the 65 mass by the grizzley 84 is adapted to be discharged forwardly into a suitable receiver (not shown).

The intermediate separating member 19 is provided with a plurality of separating chambers 86, 87 and 88. The chamber 86 is the receiving chamber which is adapted to receive the material from the upper box 17 and has a portion thereof positioned immediately below the grizzley or screen 84. The chamber 86 is pro- 75

vided with an end wall 89 and a pair of bottom walls 90 and 91. The bottom wall 90 extends in parallel relation to the lower edge of the sides 40 and the bottom wall 91 extends forwardly and upwardly thereby forming a pocket 92 at the angle between the two bottom members 90 and 91. An inner bottom wall 93 is mounted on top of the bottom 90 and an inner bottom 94 is mounted on top of the bottom 91. In practice the two bottom members 93 and 94 are formed integrally with each other and are formed out of sheet metal such as amalgamated copper or other suitable metal.

The forward end of the separating chamber 86 is provided with a vertically downwardly extending wall 95 forming a rear wall of the succeeding chamber 87. The rear end of the chamber 87 has a pocket 96 which is substantially lower than the height of the forward end. The chamber 86 is provided with a bottom wall 97 and an inner bottom 98 formed of amalgamated copper or the like. There may be as many intermediate chambers 87 as may be desired depending only on the length of the box 87. The foremost chamber 87 discharges into the last chamber 88 which has a bottom wall 99 extending between the sides 40 and an inner bottom 100 is mounted on the inner surface of the bottom member 99. Preferably the ends of the side walls 40 are cut off on an angle 30 as at 101 so that the side walls 40 may be in vertical alignment with the side walls 38 of the lower member 18.

The material including water and ore is discharged over the upper forward end of the bottom wall 100 into a receiving chamber 102 carried by the lower member 18. The receiving chamber 102 is provided with a bottom wall 103 secured between the side walls 38 and an inner bottom 104 formed of amalgamated copper or other suitable metal is mounted on the inner surface of the bottom 103. A lower pocket 105 is formed in the receiving chamber 102 within which quicksilver or the like may be positioned. A plurality of intermediate chambers 106 are positioned forwardly of the receiving chamber 102 and each intermediate pocket 106 is provided with a lower bottom 107 and an inner bottom 108. The bottom members 107 and 108 are inclined to the horizontal in a direction reverse to the movement of the material so as to form a pocket 109 between the rear end of the inner wall 108 and a vertical wall 110. The vertical wall 110 extends between the side members 38 and the foremost end wall 110 is secured to the bottom 103 of the receiving chamber 102. The last or discharging chamber 111 is disposed at the lower end of the lower box 18 and is adapted to discharge the water and other material into a suitable receiver (not shown).

60 The ore including water is discharged into the upper box 18 and each pocket 82 in the upper box 18 is adapted to have quicksilver 82 positioned therein. The power member 58 is adapted to transversely rock the superposed boxes and the platform 11 so as to move the material from side to side. The water may pass through the opening 80 in the baffle members 77 which are adjusted as to height by angle so that the ore may readily pass thereover. The initially separated precious metal is adapted to drop vertically downwardly over the baffle member 77 into the pockets 81 where the precious metal will be amalgamated with the quicksilver 82. In the initial discharge of the ore and water into the upper member 17 there is also a discharged

heavier material in the form of crushed rock or pebbles which in the transverse rocking of the device will form grinding means for grinding the ore as the ore is moved transversely over the riffles 76. When the material leaves the last chamber 5 74a the larger grinding members will be separated from the finer material and the water by means of the grizzly or screen into the receiving chamber 86 of the intermediate box 19, and then moves forwardly and downwardly until it is discharged from the last chamber 88 into the receiving chamber 102 of the lower box 18. During the passage of the material through the intermediate box 19 the finer precious metal will be amalgamated with quicksilver in the pockets 92 15 and 96. The material including water will pass forwardly from the receiving chamber 102 through the intermediate chambers 106 into the discharge chamber 111. The material separated from the ore in the lower box 18 will be retained 20 in the pockets 109 where the material will be amalgamated with quicksilver or the like.

A mill constructed according to this invention may be mounted in places which are inaccessible to mills at present available and may be operated 25 by an internal combustion engine, electric motor, water power or other suitable power means available at the particular location.

What I claim is:

1. A device as set forth comprising a base, a 30 platform, means at the opposite ends of the platform rockably securing said platform to said base, a plurality of superposed troughs above said platform, means pivotally securing the adjacent ends of said troughs together, a plurality of wedge 35 members between said troughs maintaining said troughs in inclined position, a pair of transversely disposed bars engaging the uppermost of said troughs, and tie rods engaging through said bars and said platform to secure said troughs against 40 movement relative to said platform.

2. A device as set forth comprising a base, a platform, means at the opposite ends of the platform rockably securing said platform to said base, means for rocking said platform, a plurality of 45 superposed troughs above said platform, means pivotally securing the adjacent ends of said troughs together, a plurality of wedge members between said troughs maintaining said troughs in inclined position, means securing said wedge 50 members in adjusted position relative to said troughs, a pair of transversely disposed bars engaging the uppermost of said troughs, and tie rods engaging through said bars and said platform to secure said troughs against movement 55 relative to said platform.

3. A device as set forth, a base, a plurality of superposed troughs, and means rockably mounting said troughs on said base for rocking movement transverse to the length thereof, each 60 trough comprising a pair of side walls, a plurality of bottom walls disposed in substantially parallel planes and inclined to the length of said side walls, the rear end of one bottom wall being disposed below the forward end of a preceding wall, 65 and a rifled inner bottom carried by each of said first bottom walls, the riffles of said inner bottom extending lengthwise of a trough.

4. A device as set forth, a base, a plurality of superposed troughs, and means rockably mounting said troughs on said base, each trough comprising a pair of side walls, a plurality of bottom walls disposed in substantially parallel planes and inclined to the length of said side walls, the rear end of one bottom wall being dis- 75

posed below the forward end of a preceding wall, a rifled bottom carried by each of said first bottom walls, the rifles of said inner bottom extending lengthwise of a trough, an upwardly projecting baffle at the forward end of each of the bottom walls of the uppermost of said troughs, and mounting means for each baffle.

5. A device as set forth, a base, a plurality of superposed troughs, and means rockably mounting said troughs on said base, each trough comprising a pair of side walls, a plurality of bottom walls disposed in substantially parallel planes and inclined to the length of said side walls, the rear end of one bottom wall being disposed below the forward end of a preceding wall, a rifled inner bottom carried by each of said first bottom walls, the rifles of said inner bottom extending lengthwise of a trough, an upwardly projecting baffle at the forward end of each of the first bottom walls of the uppermost of said troughs, means swingably mounting said baffles, and means holding said baffles in angularly adjusted position relative to said first bottom walls.

6. A device as set forth, a base, a plurality of superposed troughs, and means rockably mounting said troughs on said base, each trough comprising a pair of side walls, a plurality of bottom walls disposed in substantially parallel planes and inclined to the length of said side walls, the rear end of one bottom wall being disposed below the forward end of a preceding wall, a rifled inner bottom carried by each of said first bottom walls, the rifles of said inner bottom extending lengthwise of a trough, an upwardly projecting baffle at the forward end of each of the first bottom walls of the uppermost of said troughs, means swingably mounting said baffles, and means holding said baffles in angularly adjusted position relative to said first bottom walls, each of said baffles including means whereby water and fine material may pass a baffle below the upper edge thereof.

7. A device as set forth comprising a base, a platform, means mounting said platform for rocking movement transverse to the length of said base, a lower trough, means pivotally securing one end of said lower trough on said platform, wedge means between said lower trough and said platform for holding said lower trough on an inclination to the horizontal, an intermediate trough, means securing one end of said intermediate trough to the upper end of said lower trough, wedge means between said lower and intermediate troughs for holding said intermediate trough at an angle to the horizontal opposed to the angle of said first trough, the lower end of said intermediate trough discharging into the upper end of said lower trough, an upper trough, means pivotally securing an end of said upper trough to the upper end of said intermediate trough, wedge means between said upper and intermediate troughs holding said upper trough at an inclination to the horizontal opposed to said intermediate trough, a grizzly at the lower end of said upper trough and inclined to the horizontal for discharging the large particles beyond the lower end of said upper trough, a pair of transversely disposed bars engaging the upper of said troughs, tie rods engaging said bars and said platform for holding said troughs against movement relative to said platform, each of said troughs including riffle members extending lengthwise thereof.

8. A device for the purpose set forth comprising a base, a platform resiliently supported in

said base, means for rockably securing the ends of the platform to the ends of the base for rocking movement of the platform transversely of its length, means for rocking the platform, a tier of superposed troughs arranged over said platform, means for maintaining said troughs at an inclination with respect to each other and to the platform, means for securing said troughs to said platform to rock in unison with the latter, the uppermost trough of said tier having an end wall of reduced height, the bottom of said uppermost trough having one end spaced from and arranged above said wall, and a downwardly inclined grizzly connected to said wall and said end and disposed over an end terminal portion of a second trough arranged directly below said uppermost trough.

9. A device for the purpose set forth comprising a base, a platform resiliently supported in said base, means for rockably securing the ends of the platform to the ends of the base for rocking movement of the platform transversely of its length, means for rocking the platform, a tier of superposed troughs arranged over said platform, means for maintaining said troughs at an inclination with respect to each other and to the platform, means for securing said troughs to said platform to rock in unison with the latter, the uppermost trough of said tier having an end wall of reduced height, the bottom of said uppermost trough having one end spaced from and arranged above said wall, a downwardly inclined grizzly connected to said wall and said end and disposed over an end terminal portion of a second trough arranged directly below said uppermost trough, means for hinging said wall to one of the end walls of said second trough, means for hinging the other end wall of the said second trough to an end wall of a third trough arranged directly below said second trough, and means for hinging the other end wall of the third trough to one end of said platform.

10. The invention as set forth in claim 9 having said means for maintaining said trough at an inclination being arranged between the troughs and between the lowermost trough and said platform and being adjustable for varying inclination of the troughs with respect to each other and with respect to said platform, the said means for maintaining said troughs at an inclination being detachably connected to said troughs.

11. A device for the purpose set forth comprising a base, a platform resiliently supported in said base, means for rockably securing the ends of said platform to the ends of the base for rocking movement of the platform transversely of its length, a tier of superposed inclined troughs arranged over said platform and hinged together and hinged to said platform, adjustable means for maintaining said troughs at an inclination with respect to each other and at an inclination with respect to said platform, means for securing said troughs to said platform to rock in unison with the latter, the uppermost trough having an end wall of reduced height, the bottom of said uppermost trough having one end spaced from and arranged above said end wall, and an inclined grizzly arranged in said uppermost trough, connected to and spanning the space between said wall and said bottom end and disposed over an end terminal portion of the trough arranged directly below said uppermost trough.
